UNITED STATES PATENT OFFICE.

WILLIAM S. PARKER, OF ROCKFORD, ILLINOIS, ASSIGNOR TO BURSON KNITTING COMPANY, OF ROCKFORD, ILLINOIS, A CORPORATION OF ILLINOIS.

NEEDLE-ACTUATING CAM FOR KNITTING MACHINES.

Application filed August 7, 1922. Serial No. 579,986.

To all whom it may concern:

Be it known that I, WILLIAM S. PARKER, a citizen of the United States, residing at Rockford, in the county of Winnebago and State of Illinois, have invented certain new and useful Improvements in Needle-Actuating Cams for Knitting Machines, of which the following is a specification.

This invention pertaining in general to knitting machines, has more particular reference to the cams for advancing and retracting the needles, especially in straight knitting machines. In these, a cam slide for each bed of needles advances and retracts the needles upon each stroke and on certain strokes the needles will be held in an idle, retracted position, the cams acting on jacks which in turn operate the needles. Tension is imposed on the needles by suitable springs for holding them against their seats and preventing displacement from the loop, especially when in the retracted position. It is desired that this spring tension shall be as light as practicable, but with the cam slides as heretofore constructed, it has been impossible to employ the desired lightness in degree of tension without impairing the knitting action. In other words, when the needles are under too light tension, there is a tendency (due to the cam construction) for them to advance during the idle stroke and skip stitches.

It is the object of the present invention, therefore, to provide means for preventing advancement of the needles during the idle strokes, thereby enabling the use of lighter tension on the needles and preventing the skipping of stitches.

Another object is to provide an improved cam structure for advancing and retracting the needles, my invention relating more particularly to the provision of supplemental cams adapted to be automatically moved into and out of operative position in which to prevent the advancement of the needles at a particular stage as will be explained more fully hereinafter.

Referring to the drawings,—

Figure 1 is a fragmentary perspective view of a needle-actuating cam slide embodying my invention;

Fig. 2 is a fragmentary vertical section through one of the needle beds of a straight knitting machine showing the location of said cam slide;

Fig. 3 is a face view of the underside of the cam slide;

Fig. 4 is a longitudinal sectional view through the cam slide taken substantially on the line 4—4 of Fig. 3; and

Fig. 5 is a cross sectional view through the cam slide taken on the line 5—5 of Fig. 3, showing a cam slide in operative relation to a needle jack.

The application of my invention will be better understood by reference to Fig. 2, which shows in brief a section through one of the needle beds of a straight knitting machine. It will be observed that the needle 8 urged against the bed plate 9 by a spring 11 is adapted to be retracted and advanced by means of a jack 12, which in turn has an upstanding lug 13 adapted to be operated by cams on a bar 14, slidable in suitable ways on the machine frame.

The cam bar carries on its underside an advancing cam 15 and double retracting cams 16 and 17, these reference numerals being generally applied. The cam 15 is fixed to a supporting part 18 extending through an opening in the slide bar 14, which part in turn is fixed to a bar 19 disposed above said slide bar and pivotally attached thereto at 21. By means of an eccentric 22 operable between the bars 14 and 19, the cam 15 may be lowered into operative position as shown in Fig. 4, in the plane of the jack lugs 13 in which either of the cam faces 23 (depending on the direction of travel) will engage the lugs 13 and advance the jacks, and likewise the needles; and by partial rotation of said eccentric, the cam 15 may be raised to an inoperative position above the lugs 13 so as not to advance the needles. The purpose of lowering and elevating the cam 15 is to throw the needles into and out of action as desired when knitting a tubular fabric, as is well known in this art.

The retracting cams 16 and 17 are fixedly but adjustably attached to the bar 14, these cams having faces 24, which by action of the jack lugs 13 are adapted to retract the needles, each surface 24 having at its heel end, an extension 25 which draws the needle down to the final stitch measurement and performs the function known in the art as "setting" the stitch. After the stitch has been set, the needles are slightly relieved by reason of the cam surface 26. Inasmuch

as each jack has a shoulder 27 which bears against the upper surface 28 of the cams 16 and 17 for limiting the retracting movement of the jacks, such surfaces are cut 5 away at 29 to compensate for the surfaces 25 at the heel end of said cams. These cams are in the present instance, respectively fixed to supporting parts 31 which are slidably guided on the guide 14 by guide plates 32 10 and adapted to be adjusted in the planes of the cam surfaces 24 which vary the distance to which the needles will be retracted, it being well known in this art that the further the needle is drawn down, the longer the loop, 15 and consequently the looser the fabric. Suitable means, not shown, is provided for rigidly securing the cam-supporting parts 31 in any adjusted position. The parts thus far described have been used prior to my 20 invention.

It is found, however, that when a comparatively light spring tension is imposed on the needles, there is a tendency for the needles to be advanced during the idle 25 stroke (that is when the advancing cam 15 is raised) partly by reason of the increased tension imposed by the first or leading cam extension 25 which engages the jack lugs and by the sudden release of such tension, 30 causing the jack plug to spring forward in the cam-way 33, assuming that the cam slide is traveling to the right, Fig. 3. This condition I have overcome by the provision of supplemental cam blocks 34 shaped to fit the cam-ways 33 and having a rear surface 35 35 in the plane of the heel surface 26. These supplemental cam blocks are adapted to be moved into and out of cam-ways 33, preferably through suitable openings 36 in extensions 37 of the cam-supporting parts 31. In the present instance, the supplemental cam blocks 34 have upwardly projecting ends 38 passing through the bar 14 and connected by means of levers 39, with the cam-supporting part 18. As shown in Figs. 1 and 4, the levers 39 pivoted intermediate their 40 ends at 41, to the bar 14 are pivotally connected at their outer ends with the extensions 38 of the supplemental cam blocks, and 45 at their inner ends with the cam-supporting part 18. As a result of this construction, said cam blocks 34 will be lowered and raised to bring their cam surfaces 35 into 50 and out of operative position in the cam-ways 33 by raising and lowering of the advancing cams 15. In other words, when said advancing cam is in the lowered operative 55 position shown in Fig. 4 (which is inverted), the supplemental cam blocks 34 will be 60 elevated to an inoperative position, and upon elevating the advancing cam 15 to an inoperative position the cam blocks 34 will thereby be lowered to their operative position, as shown in Fig. 1 (which is likewise 65 inverted). With the supplemental cam

blocks in said operative position in which their surfaces 35 form a continuation of the surfaces 26 of the retracting cams, the cam lugs 13 in retracted position will ride across the extensions 26 and against the surfaces 70 35 which prevent said lugs from advancing in the cam-ways 33 after the sudden release from the tension imposed by the cam extension 25. The supplemental cam blocks 34 75 provide, therefore, a positive means for preventing the needles from being advanced during the idle stroke, thereby eliminating the dropping of stitches, as explained above. It follows that this construction enables the use of lighter spring pressure on the needles, and is a factor in promoting longevity 80 of the machine and accuracy in knitting.

It is believed that the foregoing conveys a clear understanding of the objects prefaced above, and while I have illustrated but a 85 single working embodiment, it should be understood that considerable change might be made in the construction without departing from the spirit and scope of the invention as 90 expressed in the appended claims:

I claim:

1. In a straight knitting machine, the combination with a cam slide having cams for advancing and retracting the needles, the advancing cam being movable into and out of operative position, of a cam supplemental to one of the retracting cams for preventing advancement of the needles from their retracted position, and means for moving said supplemental cam to inoperative 100 position upon movement of the advancing cam to operative position.

2. In a straight knitting machine, the combination with the needle-actuating cam slide which carries spaced retracting cams and an interposed advancing cam, the latter adapted to be lowered and raised to and from the operative position in which a cam-way is defined between the cams for the passage of the jack lugs, of supplemental cam blocks movable into and out of said cam ways at the heel end of the retracting cams, and means for automatically moving said supplemental cam blocks into and out of said cam-ways.

3. In a knitting machine, a needle-actuating cam slide for advancing and retracting cams, the advancing cam being movable into and out of operative position and each retracting cam having an extension at its heel end for setting the stitch, and supplemental cams adapted to form continuations of the heel ends of said retracting cams.

4. In a knitting machine, a needle-actuating cam slide for advancing and retracting cams, the advancing cam being movable into and out of operative position and each retracting cam having an extension at its heel end for setting the stitch, supplemental cams adapted to form continuations of the heel 130

ends of said retracting cams, and means operated by said advancing cam for moving said supplemental cams into and out of operative position.

5. In a knitting machine, a needle-actuating cam slide for advancing and retracting cams, the advancing cam being movable into and out of operative position and each re-

tracting cam having an extension at its heel end for setting the stitch, supplemental cams adapted to form continuations of the heel ends of said retracting cams, and means for rendering said supplemental cams inoperative when said advancing cam is rendered operative, and vice versa.

WILLIAM S. PARKER.
